UNITED STATES PATENT OFFICE.

GEORGE F. FISHER, OF NORTH TONAWANDA, NEW YORK.

MORTAR-GAGE.

No. 823,593.

Specification of Letters Patent.

Patented June 19, 1906.

Application filed July 5, 1904. Serial No. 215,440.

To all whom it may concern:

Be it known that I, GEORGE F. FISHER, a citizen of the United States, residing at North Tonawanda, in the county of Niagara 5 and State of New York, have invented certain new and useful Improvements in Mortar-Gages, of which the following is a specification.

This invention relates to mortar-gages whereby the building-blocks preparatory to setting the same are faced on two adjoining sides with mortar; and its object is to provide a device of this character which is adapted to receive different sizes of building-blocks and with which the depth of mortar or cement and the amount of surface to be covered may be readily and accurately gaged.

The invention may be said to consist in 20 the elements of construction and combination of parts described and claimed, and illustrated in the accompanying drawings, wherein—

Figure 1 is a perspective view of the device. Fig. 2 is a front elevation of the same. Fig. 3 is a vertical section taken on line 3 3, Fig. 2. Fig. 4 is a horizontal section taken on line 4 4, Fig. 2. Fig. 5 is a vertical section taken on line 5 5, Fig. 3. Fig. 6 is a 30 fragmentary view showing the abutment and laterally and vertically adjustable gage member, the guide-yoke and the gage-yoke being shown as separated.

A indicates the frame or casting, which is 35 provided with an integral upright abutment B. The latter comprises a lower horizontal flange B', an upper horizontal flange B², upright side flanges B³, and a strengthening-web B⁴, which is preferably cored out, so as 40 to secure lightness.

C is the adjustable gage member, which is 45 adapted to receive the building-block to gage the depth of mortar and the extent of surface to be covered. It comprises a vertically-adjustable guide-yoke C' and a laterally-adjustable gage-yoke C². The former consists of an upper cross-bar c and depending guide-bars c', which are sufficiently spaced to receive the side flanges of the abutment and are guided and limited in their vertical movement by bolts C³, which pass through vertical slots b in the side flanges of the abutment and engage with the inner faces of depending guide-bars c'. Absolute 55 verticality of movement of the guide-yoke is insured by upright guide-notches a in the

frame on either side of the side flanges of abutment B. These guide-notches are of such size as to exactly receive the depending guide-bars c' and, together with bolts C³, render the movement of the guide-yoke absolutely rectilinear. The gage-yoke also comprises a horizontal cross-bar c² and depending side bars c³, the latter being sufficiently spaced exactly to receive the depending 60 guide-bars c'. The gage-yoke is made laterally adjustable by horizontal slots c⁴ in its side bars, which receive countersunk bolts c⁵, Fig. 4, that enter the guide-bars of the guide-yoke. It will be noted that the bearing-faces of the upper, lower, and side flanges of the abutment and the bars of the guide-yoke all lie in the same plane, whereby the building-block is evenly supported. The outer end of the frame forms a level base D, 70 75 upon which the block may be placed.

E designates a supplemental gage member mounted at the extremity of the base D and likewise adapted to receive the block for the purpose of gaging the mortar. It consists of 80 a laterally and vertically adjustable yoke comprising an upper cross-bar E' and depending side bars E², which are preferably strengthened by a web E³. Supplemental gage member E is rendered adjustable in two 85 directions by horizontal slots D' in the side of the base and vertical slots e in side bars E². Bolts e' pass through each pair of horizontal and vertical slots and are tightened by nuts e². In use unless it is desired to point the 90 wall both from the inner and outer sides the supplemental gage member will be dispensed with. In this case it is apparent that the base D might also be omitted; but, as stated, it is useful for supporting the block. Supposing that the supplemental gage member 95 is to be used, this member is swung down so as to clear the outer end of the base and the block is placed upon the latter with one face engaging with the top and bottom and one of 100 the side flanges of the abutment. The latter being formed integral with the frame steadies the block while the gage member C is being adjusted to the proper height and to expose the proper amount of surface on the 105 block. Bolts C³ and c⁵ having been tightened, the supplemental gage member is swung in place, adjusted by means of the horizontal and vertical slots, and the nuts e' are tightened. The operator then takes a 110 supply of mortar upon his trowel and passes the latter rapidly over the two adjoining ex-

posed surfaces of the block, the laterally-adjustable guide-yoke, as will be apparent, operating to gage the depth and width of the mortar strip exactly, as shown in dotted lines, 5 Fig. 3. It will be noted that bolts c^5 are countersunk, so that they form no obstruction to the passage of the trowel over the depending side bars c^3 .

What is claimed as new is—

- 10 1. In a mortar-gage, the combination with a frame, of a gage member mounted on said frame and adapted to lie against adjoining edges of a building-block to gage the thickness of the layer of mortar to be applied to 15 said block.
- 20 2. In a mortar-gage, the combination with a frame, of a gage member vertically adjustable on said frame and adapted to lie against adjoining edges of a building-block to gage the 25 thickness of the layer of mortar to be applied to said block.
- 30 3. In a mortar-gage, the combination with a frame, of a gage member adjustable on said frame and adapted to lie against adjoining edges of a building-block to gage the thickness of the layer of mortar to be applied to 35 said block.
- 40 4. In a mortar-gage, the combination with a frame comprising a base and an upright abutment against which a building-block is set, of a gage member carried on said abutment and adapted to lie against adjoining edges of the building-block to gage the thickness of the layer of mortar to be applied to 45 said block.
- 50 5. In a mortar-gage, the combination with an abutment against which a building-block is to be set, of a gage member adapted to lie against adjoining edges of the building-block to 55 gage the thickness of the layer of mortar to be applied to the block and being laterally adjustable to gage the extent of surface on the block to be covered with mortar.
- 60 6. In a mortar-gage for applying a layer of mortar to a block, the combination with a suitable frame to support a building-block, of an adjustable gage member supported thereon and adapted to lie against the marginal portion of one or more surfaces of a block for 65 gaging the thickness of the layer of mortar to be applied and for gaging the extent of surface to be covered with mortar.
- 70 7. In a mortar-gage, an upright abutment comprising an upper horizontal flange, a lower horizontal flange, and upright side flanges, the bearing-surfaces of said flanges all lying in the same plane; combined with a gage member comprising a laterally-adjustable part and a vertically-adjustable part.
- 75 8. In a mortar-gage, an upright abutment comprising an upper horizontal flange, a lower horizontal flange, and upright side flanges and a cored-out web connecting said flanges, the bearing-surfaces of said flanges all lying in the same plane; combined with a

gage member comprising a laterally-adjustable part and a vertically-adjustable part.

9. In a mortar-gage, the combination with a frame, of a two-part gage member mounted thereon and adapted to receive a building-block, one part of the gage being adjustable on the other part thereof and adapted to lie against two adjoining edges of the block to gage the thickness of the layer of mortar to be applied thereto. 75

10. In a mortar-gage, the combination with a frame having upright notches, and an upright abutment; of a gage member adapted to receive a building-block and comprising two parts, one part being vertically adjustable in said notches, and the other part being laterally adjustable on the first part. 80

11. In a mortar-gage, the combination with a frame having upright notches, and an upright abutment mounted between said notches; of a gage member adapted to receive a building-block and comprising two parts, one part being vertically adjustable on the abutment in said notches, and means for laterally adjusting the other part on the first part. 85

12. In a mortar-gage, the combination with a frame having upright notches, and an upright abutment having vertical slots; of a gage member adapted to receive a building-block and comprising two parts, one part being adapted to slide in said notches and having bolts engaging with said slots, and the other part being laterally adjustable on the first part. 90

13. In a mortar-gage, the combination with a frame having an upright abutment; of a gage member adapted to receive a building-block and comprising a guide-yoke and a gage-yoke, said guide-yoke fitting over the abutment and comprising an upper horizontal cross-bar and depending guide-bars vertically adjustable on said abutment, and said gage-yoke fitting over the guide-yoke and comprising an upper horizontal cross-bar and upright side bars laterally adjustable on the guide-yoke. 100

14. In a mortar-gage, the combination with an abutment having an upright bearing-surface; of a gage member adapted to receive a building-block comprising a vertically-adjustable guide-yoke and a laterally-adjustable gage-yoke, said guide-yoke fitting over the abutment and comprising an upper horizontal cross-bar and depending guide-bars, all said bars having bearing-surfaces lying in the same plane with the bearing-surfaces of the abutment. 115

15. In a mortar-gage, the combination with an upright abutment; of a gage member adapted to receive a building-block and comprising a guide-yoke fitting over the abutment and being vertically adjustable thereon, and a gage-yoke fitting over said guide-yoke and having upright side bars provided 120

130

- with horizontal slots, and bolts countersunk in said slots and entering the guide-yoke.
16. In a mortar-gage, the combination with a frame and an adjustable gage member thereon adapted to receive a building-block; of a supplemental adjustable gage member mounted on the frame opposite the first gage member, said supplemental gage member being also adapted to receive the block.
17. In a mortar-gage, the combination with a frame and a gage member comprising a laterally-adjustable part and a vertically-adjustable part and adapted to receive a building-block; of a supplemental gage member mounted on the frame opposite the first gage member and also adapted to receive the block.
18. In a mortar-gage, the combination with a frame and an adjustable gage member thereon adapted to receive a building-block; of a laterally and vertically adjustable supplemental gage member mounted on the frame opposite the first gage member, said supplemental gage member being also adapted to receive the block.
19. In a mortar-gage, the combination with a frame and an adjustable gage member thereon adapted to receive a building-block; of a supplemental adjustable gage member mounted on the frame opposite the first gage member, said supplemental gage member being adapted to be swung down clear of the

building-block and being also adapted to receive the block when in operative position.

20. In a mortar-gage, the combination with a frame having horizontal slots, and an adjustable gage member mounted thereon adapted to receive a building-block; of a supplemental gage member also adapted to receive the block, said supplemental gage member comprising a yoke having an upper horizontal cross-bar and upright side bars having vertical slots, and means passing through the slots in the frame and supplemental gage member for adjustably securing said supplemental gage member.

21. In a mortar-gage, the combination with a frame having horizontal slots, and an adjustable gage member mounted thereon adapted to receive a building-block; of a supplemental gage member also adapted to receive the block, said supplemental gage member comprising a yoke having an upper horizontal cross-bar and upright side bars having vertical slots, bolts passing through the slots in the frame and supplemental gage member, and means for tightening said bolts.

In testimony whereof I have affixed my signature in the presence of two subscribing witnesses.
